SHELF BRACKET SUPPORT UNIT

Franklin Delano Robertson, 1480 E. Grand,
Pomona, Calif. 91766

Filed Dec. 14, 1970, Ser. No. 26,460

Term of patent 14 years

Int. Cl. D6—99

U.S. Cl. D6—194

FIG. 1 is a front perspective view of a shelf bracket support unit showing my new design;

FIG. 2 is a front elevational view;

FIG. 3 is a side elevational view; and,

FIG. 4 is a top plan view thereof.

I claim:

The ornamental design for a shelf bracket support unit, as shown.
